CLARENCE W. CONNALEY, OF AUSTIN, TEXAS.

MACHINE FOR CRACKING NUTS.

1,143,843.

Specification of Letters Patent. Patented June 22, 1915.

Application filed June 17, 1914. Serial No. 845,640.

To all whom it may concern:

Be it known that I, CHARLES W. McDONALD, a citizen of the United States, residing at Austin, in the county of Travis and State 5 of Texas, have invented a new and useful Machine for Cracking Nuts, of which the following is a specification.

The invention relates to improvements in machines for cracking nuts.

10 The object of the present invention is to improve the construction of machines for cracking nuts and to provide a simple, practical, and efficient nut cracking machine of strong and durable construction, which will 15 be easy and cheap to manufacture.

A further object of the invention is to provide a nut cracking machine of this character, designed for cracking various kinds of nuts and capable of rapid and convenient 20 operation and of enabling nuts of various sizes to be properly cracked, so that the meat can be taken out in perfect condition.

With these and other objects in view the invention consists in the construction and 25 novel combination of parts hereinafter fully described, illustrated in the accompanying drawing, and pointed out in the claims appended hereto, it being understood that various changes in the form, proportion, size 30 and minor details of construction, within the scope of the claims, may be resorted to without departing from the spirit or sacrificing any of the advantages of the invention.

35 In the drawing:—Figure 1 is a perspective view of a nut cracking machine constructed in accordance with this invention. Fig. 2 is a horizontal sectional view of the same. Fig. 3 is a transverse sectional view on the line 3—3 of Fig. 2.

Like numerals of reference designate corresponding parts in all the figures of the drawing.

40 In the accompanying drawing, in which is illustrated the preferred embodiment of the invention, 1 designates the frame of the machine provided with a horizontal bed plate 2 having a flat lower face to fit the upper face of the top 3 of a table or other support. The frame, which consists of a single casting of malleable metal, or other suitable material, is also provided with a lower vertical flange 4 depending from the plate 2 and adapted to fit against the front 45 edge of the table top 3, so that the nut

cracking machine may be firmly secured to the table top by a clamp 5. The clamp 5 consists of a substantially L-shaped arm located at the inner or rear portion of the flange 4 and composed of a vertical portion 60 extending downwardly from the bed plate at the front of the flange 4 to a point below the same, and a horizontal portion extending rearwardly beyond the flange and having its terminal enlarged and provided with 65 a threaded opening for the reception of a thumb screw 6. The L-shaped arm of the clamp co-operates with the plate 1 to form a clamp yoke in which the edge of the table is securely held by the thumb screw. When 70 the frame is clamped to the table, it is firmly and securely fastened to the same without liability of wobbling when pressure is applied to the machine for cracking the nut.

The plate 2 is provided at one end with a 75 reduced extension 7 from which projects a fixed jaw 8 formed integral with the frame of the machine and located at one end thereof. The front depending flange preferably extends along the frame from a point beneath the fixed jaw to a point beyond the clamp 5, and the plate 2 projects in advance of the flange 4, forming a flanged structure of great strength and durability. The frame is provided at the inner rear portion of the 80 plate 2 with a guide 9 receiving a slideable pressure bar or member 10 and consisting of a rear vertical wall 11 and a top wall 12, the guide being open at the front and the frame being provided at the top and bottom of the 85 same with forwardly projecting upper and lower supporting arms 13 and 14. The arms are formed integral with the guide and the latter is provided at the upper and lower portions of its open front with vertical 90 shoulders 15. The slideable pressure bar or member 10, which is movable horizontally through the guide, has smooth upper and lower portions or flanges 16 fitting in the upper and lower portions of the guide and 95 located above and below a longitudinal series of spur teeth 17 forming a rack and projecting at the open front of the guide. The projecting rack forms upper and lower shoulders 18 which are adapted to fit against 100 the inner contiguous faces of the supporting arms 13 and 14, as the said rack slides between and across the same. The bed plate 2 is provided at the rear portion of its upper 105 face with a recess 19 to form a way for the 110

lower flange of the slidable pressure bar or member. The bottom of the recess 19 is arranged in flush relation with the bottom of the guide 9, and the said recess also forms a front shoulder 20, which is arranged in flush relation with the lower shoulder of the said guide. By this construction and arrangement the slidable bar or member is properly guided and held against vertical and lateral movement.

The upper and lower supporting arms, which are braced by an integral vertical post or connecting portion 21, are provided with inner and outer vertically aligned openings 22 and 23 for the reception of inner and outer pins 24 and 25, which form shafts or spindles for an intermediate gear 26 and an outer gear 27 mounted between the supporting arms and meshing with each other. The pins, which are provided at their upper ends with heads, are also preferably headed at their lower ends, but any other desired construction of shaft or spindle may be employed. The gears 26 and 27 are provided with spur teeth and the intermediate gearing meshes with the spur teeth of the rack. The outer spur gear is formed integral with an operating lever 28, terminating at its outer end in a suitable grip or handle 29 and adapted to be oscillated to actuate the slid- 30 able bar or member. By employing the intermediate spur gear the slidable bar or member and the lever 28 move in the same direction, which greatly facilitates a convenient and rapid operation of the machine.

The fixed jaw 8 extends upwardly and inwardly at an inclination, and it is preferably provided at its inner face with a concavity or seat 30 to receive one end of a nut 31, and the slidable bar or member 10 is provided with a jaw or head 32 laterally enlarged at the front side and provided with a concavity or seat 33 offset from the median longitudinal plane of the slidable bar or member and arranged in alignment with the seat or concavity 30 and with the pitch line of the teeth of the intermediate gear and the rack of the slidable bar or member, as indicated by the dotted line *a* in Fig. 2 of the drawing. By this construction, the power is applied to the slidable bar or member in line with the center of the nut, and an accurate cracking of the same is produced. When the lever is swung horizontally in the direction of the fixed jaw, the slidable bar or member is simultaneously carried in the same direction, thereby applying pressure to the nut and enabling the same to be easily and rapidly cracked. A movement of the operating lever in the opposite direction carries the slid- 55 able bar or member in the opposite direction, and opens the jaws of the machine.

What is claimed is:—

1. A nut cracking device including a frame comprising a horizontal plate, a ver-

tical flange depending from and extending longitudinally of the plate and arranged to fit against the edge of a table or other support, a guide extending upwardly from the horizontal plate, which constitutes the bottom wall of the guide, a fixed jaw rigid with and extending upwardly from the said plate and arranged in spaced relation with the guide, a clamp depending from the frame and extending in rear of the flange for engaging the lower face of the top of the table, a horizontally movable slide or member mounted in the said guide and provided at one end with a head or jaw arranged to coöperate with the fixed jaw, and gearing for actuating the slide or member, said gearing including a horizontally swinging operating lever.

2. A nut cracking machine including a horizontal plate adapted to be secured upon a table or other supporting surface, a fixed jaw rigid with and extending upwardly from one end of the plate, a guide located at the other end of the plate and composed of a rear wall, a bottom wall formed by the said horizontal plate, and a top wall, said guide being open at the front, and upper and lower supporting arms extending forwardly at the open front of the guide, a horizontally movable slide or member mounted in the said guide and provided with a jaw or head arranged to coöperate with the fixed jaw, said slide or member being also provided at the front with a rack, an intermediate gear mounted between the inner portions of the supporting arms and meshing with the said rack, and an operating handle provided with a gear mounted between the outer portions of the said arms and meshing with the intermediate gear, whereby when the lever is oscillated the slide or member will be simultaneously moved in the same direction.

3. A nut cracking machine including a horizontal plate provided at one end with a fixed jaw rigid with and extending upwardly from the plate, a guide arranged at the other end of the plate and composed of a rear vertical wall and top and bottom walls, said guide being provided with an opening of a height less than that of the guide and forming upper and lower shoulders, upper and lower supporting arms extending from the guide at the top and bottom of the said opening, a horizontally movable slide mounted in the guide and provided at the front with a rack and having curved upper and lower longitudinal flanges slidable in the top and bottom portions of the guide and fitting against the said upper and lower shoulders, said rack projecting forwardly through the said front opening in the guide, and means for actuating the slide including a gear mounted between the supporting arms and meshing with the rack.

4. A nut cracking machine including a horizontal plate adapted to rest upon and be secured to a table or other supporting surface and provided at one end with an integral inclined jaw extending upwardly and inwardly from the said plate, a guide extending upwardly from the horizontal plate at the other end thereof and having its bottom wall formed by the said plate, said 10 guide being open at the front, spaced upper and lower horizontal supporting arms extending from the guide at the open front thereof, a horizontally movable slide mounted in the guide and slidable along the said 15 plate and provided at the front with a rack, said slide being also provided with a jaw arranged to coöperate with the said fixed jaw, and gearing supported by the said arms and coacting with the rack for reciprocating the 20 slide.

5. A nut cracking machine comprising a frame including a horizontal plate, a slide

or member provided at the front with a rack and having a head or jaw laterally enlarged at the side of the front of the 25 slide or member and having a rack at the front, a gear mounted on the frame and meshing with the rack, said laterally enlarged head or jaw having a socket located in alinement with the pitch line of the meshing teeth of the rack and the gear, means for rotating the gear, and a fixed inclined jaw extending upwardly and rearwardly from the front end of the plate and arranged to coöperate with the movable jaw or 30 head.

In testimony, that I claim the foregoing as my own, I have hereto affixed my signature in the presence of two witnesses.

CHARLES WALTON McDONALD.
